Patented Dec. 7, 1926.

UNITED STATES PATENT OFFICE.

JOSEPH C. DEVICK, OF CHICAGO, ILLINOIS, ASSIGNOR, BY MESNE ASSIGNMENTS, TO
F. C. AUSTIN MACHINERY COMPANY, A CORPORATION OF ILLINOIS.

FEEDER FOR ELEVATORS.

Application filed September 25, 1919, Serial No. 326,193. Renewed July 10, 1926.

This invention relates to machinery or apparatus for elevating materials from the street, as for example in the making of concrete or cementitious mixtures. The materials, such as sand, crushed rock or gravel, are dumped on the street, and the buckets of the conveyer or elevator carry the same upwardly to a point where the materials are then discharged into the hopper of the mixer. The materials are fed to the lower end of the elevator in various ways, sometimes by shovelling, and various devices have also been proposed and employed for automatically feeding the materials to the lower end of the elevator. This invention, therefore, relates more particularly to means or devices for feeding the materials from the ground or street to the lower end of the elevator, so that the buckets of the latter will be properly filled.

Generally stated, the object of the invention is to provide an improved construction and arrangement whereby a feeding device of this character will more positively and satisfactorily feed or sweep the materials from the ground into the buckets at the lower end of the elevator, so that the feeding action will be practically continuous, thus insuring a complete or proper filling of the buckets as they travel successively around the lower end of the elevator.

It is also an object to provide certain details and features of construction and combinations tending to increase the general efficiency and the desirability of a feeding device of this particular character.

To the foregoing and other useful ends the invention consists in matters hereinafter set forth and claimed and shown in the accompanying drawings, in which—

Fig. 1 is a side elevation of a street machine having an elevator provided at its lower end with a feeder embodying the principles of the invention, the upper portions of said machine being shown broken away for convenience of illustration.

Fig. 2 is an enlarged side elevation of the lower end of the elevator, showing the feeding mechanism by which the materials are pushed forward from the ground into the oncoming buckets.

Fig. 3 is a plan of the feeding device shown in Fig. 1, showing the lower end portion of the elevator in position between the two feeders which operate intermittently to

push the materials into position where they will be taken up by the buckets of the elevator.

Fig. 4 is a front elevation of the construction shown in Fig. 2.

Fig. 5 is a detail horizontal section on line 5—5 in Fig. 2.

As thus illustrated, the street machine is of a well known type comprising a body 1 mounted upon front and rear wheels 2 and 3, and having an engine 4 for the operation of the machine. The elevator comprises a beam or frame 5 mounted to tilt about the horizontal axis provided by the shaft 6, and an endless belt 7 arranged on upper and lower sprockets (the upper sprockets are not shown) to carry the buckets 8, which latter are all of any suitable or known character. Power is communicated from the engine through the sprocket chain 9 to the shaft 6, and from the latter through the sprocket chain 10 to the upper end of the elevator, so that the sprocket chains or belts 7 and the buckets 8 are operated in the usual and well known manner, causing the buckets which are upside down to travel downwardly, and causing the buckets in the rear which are right side up to travel upwardly. It will be seen that the buckets 8, while travelling around the lower end of the elevator, pass or sweep close to the ground or surface of the street upon which the machine is standing. The construction of a machine of this general type is well known and well understood, and does not require further description.

The devices for feeding the materials to the lower end of the elevator are as follows: Brackets or castings 11 are suitably secured to the lower end of the elevator, at opposite sides of the bucket conveyer, and are adapted to provide bearings for the vertically disposed shafts 12, one at each side of the machine, which are connected by bevel gearing 13 with the horizontal shaft 14 upon which are mounted the sprockets for the lower end of the elevator, whereby the shaft 14 is driven by the bucket conveyer. In turn, therefore, the shafts 12 are rotated at the desired speed. Each shaft 12 is provided at its lower end with a crank arm 15, and each casting 11 is formed with a guide 16, these two guides being parallel and extending longitudinally of the machine at opposite sides of the elevator. The shovel-like

members 17 are pivoted at 18 upon the crank arms 15, and have rigid arms 19 provided with means 20, such as a roller or round portion, to engage the guides 16, in the 5 manner shown. Thus the rotation of the shafts 12 causes the shovel-like members 17 to move toward and away from each other, and causes the tip or point 21 of each shovel-like member to have an elliptical, or substantially elliptical, path of travel during 10 its operation. Thus each shovel-like member is drawn backward toward the guide 16, the roller or other portion 20 keeping the face of the member toward the materials on 15 the ground, and then the said member is moved outwardly a distance, and then the motion is reversed to bring the member backward toward the mass of materials at the lower end of the elevator, the limit of movement 20 of said member in this direction (toward the buckets) being indicated in dotted lines at 22 in Fig. 5, from which it will be seen that the two members 17 reach out and bury themselves in the materials and then 25 move toward each other to carry or shove the materials into the path of the oncoming buckets. The action, therefore, is somewhat like ordinary shovelling, except that the shovel-like members operate or move in a 30 horizontal plane instead of moving up and down. The two shovel-like members are operated at a speed which will give the best results, and as the elevator continues in operation the machine can be moved backward 35 to push the lower end of the elevator and the two shovel-like members into the mass or heap of materials resting on the ground, thereby keeping the feeding means constantly at work shovelling the materials into 40 the path of the buckets at the lower end of the elevator. The operation of the shovel-like members is positive, as each member will push a quantity of the materials forward into the path of the buckets. 45 When the two members move apart, as indicated in dotted lines at 22 in Fig. 3, the machine can then be shifted a little to bring the lower end of the elevator closer to the heap or mass of materials, and the two shovel-like members will then cooperate to 50 push or sweep the materials directly into the path of the buckets. Always, though, as shown, the two shovel-like members 17 face each other, or face the heap or mass 55 of materials, and have a to and fro or back and forth movement toward and away from each other. Also, the arms 19 may be provided with depending flanges 23 to shovel the materials toward the buckets, and to 60 serve as guards for preventing the materials from spreading laterally away from the loading position of the buckets.

What I claim as my invention is:

1. In combination with an elevator for 65 conveying materials upwardly, a shovel-

like member for pushing the materials to the lower end of said elevator, mechanism for operating said member back and forth, and means for controlling said member, so that said member always faces the materials, said mechanism comprising a vertically disposed shaft having a crank thereon, which crank is pivotally connected to said shovel-like member, and said controlling means comprising a guide and means connected with said member to engage said guide. 75

2. In apparatus for feeding materials, the combination of a pair of shovel-like feeding members operating together, a 80 guide, means connected with said members to engage said guide and mechanism rotating about a vertical axis to operate each of said members back and forth and to swing them laterally, so that said members always 85 face the materials, said members being movable simultaneously toward and away from each other by said mechanism.

3. In a device for feeding materials, the combination of a shovel-like member arranged to swing in and out about a vertical axis, mechanism for operating said member, and means whereby said vertical axis is allowed to shift back and forth in a straight 90 line during the operation of said member. 95

4. In a device for feeding materials, the combination of a shovel-like member arranged to swing in and out about a vertical axis, mechanism for operating said member, and means whereby said vertical axis is allowed to shift back and forth in a straight 100 line during the operation of said member, in combination with instrumentalities whereby said device is portable and can be moved forward into a mass or heap of said materials. 105

5. In combination with an elevator for conveying materials upwardly, a pair of shovel-like members operating together for pushing the materials to the lower end of said elevator, mechanism for operating each of said members back and forth and laterally, and means for controlling said members, so that said members always face the materials, in combination with instrumentalities whereby said elevator and said members are portable and may be pushed forward into a mass or heap of said materials. 110 115

6. In a device for feeding materials, the combination of a shovel-like member arranged to swing in and out about a vertical axis, mechanism for operating said member, and means whereby said vertical axis is allowed to shift back and forth in a straight 120 line during the operation of said member, said mechanism comprising a crank pivoted on said member, the latter having a rigid arm, and said means comprising a guide 125 for the end of said arm in combination with 130

a flange depending from said arm to engage the materials.

7. In combination with an elevator for conveying materials upwardly, a pair of shovel-like members operating together for pushing the materials to the lower end of said elevator, mechanism for operating each of said members back and forth and later-

ally, and means for controlling said members, so that said members always face the materials, said controlling means comprising arms rigid with said members, in combination with flanges depending from said arms to engage the materials. 10

JOSEPH C. DEVICK.
